RADIO PLURAL PROGRAM RECEIVING SYSTEM

Morris W. Askin, Washington, D. C.

Application July 5, 1929, Serial No. 376,252

19 Claims. (Cl. 250—9)

This invention relates to wireless receiving apparatus and has especial reference to a combination wireless receiving set.

In the reception of wireless waves, especially such as are used in the art of wireless telephony, it is frequently desirable to receive waves of different frequencies at the same time. For instance, a hotel wired for the transmission of broadcast programs to its various rooms may desire to afford its guests the choice of two programs.

One important object of the present invention is the provision of novel and improved receiving apparatus for wireless waves whereby two programs of different wave frequencies may be received over a single antenna.

Also, there are times when it is desirable to have ample volume in the reproduced sounds.

A second important object of this invention is to provide, in apparatus of this class, means whereby the receiving apparatus may be quickly changed from apparatus receiving two sets of waves of different frequencies to apparatus having greatly increased amplifying power for waves of any selected frequency.

A third important object of the invention is to provide a double set of wireless apparatus in which the two sets may be used individually or together.

A fourth important object of the invention is to provide a novel and improved arrangement of two sets of receiving apparatus of this class wherein the sets may be used individually or may be coupled by a simple switch arrangement either to bring the radio frequency amplifying elements of the two sets in series to increase the amplification reaching the detector or to bring the two audio frequency portions of the sets in multiple so as to substantially double the current strength reaching the loud speaker.

A fifth important object of the invention is to so arrange the two sets or units that one of the two may be bought by a user at one time and the other set or unit may be bought at some future time and either readily coupled to the first set or unit to produce the double set results of selective coupling or used alone.

Another object of this invention is to provide means so that when a company of men in military service having radio communication with a main commanding post out of the range of such communication, they may couple their radio with a radio of another company of men so that signals can be obtained from a longer distance.

And a still further object is to have a radio

receiving outfit whereby one section of the radio is to receive sound and the other section of the total radio is to receive radio vision. Wires for the radio vision apparatus connected thereto make a combined television receiver capable of receiving two distinctive wave lengths for each purpose of the same instant.

A still further application of my invention is to superheterodyne receiving sets wherein the switching and circuit system which I provide will greatly increase the usefulness of such a receiving set. Any receiving system is applicable to the spirit of my invention, whether operated by antenna, or by loop, or by two loops, or by antenna and loop, to receive the plural program which I describe.

This invention contemplates the association of radio receivers as explained hereinafter, whether they be battery operated or connected directly to the electric lines, whatever the type of circuit employed in the receiver and irrespective of the type of radio tube employed. It also contemplates the association of radio receivers for the reception of any type of signal, (audible or visual) and of any frequency (long and short wave). It is the purpose of this invention to combine a plural number of receivers, each of which may be used independently of the others for independent purposes, into one receiver to provide either combined audible and visual entertainment or to provide a stronger signal. The combined receivers also provide, if they be sensitive to the same wave frequency, for an easy method of securing an uninterrupted radio program should one of the radios fail, as for example by the burning out of a tube.

A further object of this invention is to provide means whereby local reception can be received with a small consumption of power since only a portion of the associated receivers may be employed for this purpose.

My system of reception can be embodied in any set so long as the object is to have a plural program receiver when desired and when a single program is desired it will send a double output to the particular speaker desired at a tremendous volume. It is possible to receive one nearby station with one section of the receiving apparatus or with both sections in parallel. That is, the radio-frequency circuit, the detector circuit, and the audio-frequency circuit of each section can operate independently, and for volume reproduction the two sections can be combined in parallel. When distance is wanted the radio-frequency circuit of one section is coupled in

series with the radio-frequency circuit of the other section, and the detector circuits are connected in parallel, and the audio circuit of one section or of both sections can be connected to 5 the loud speaker or other reproducing means.

It is further to be observed that by means of my arrangement, selection may be made for short wave or long wave reception in sets arranged for both short waves and long waves. Also, in a 10 combined television and sound reception set, a switch may be used to connect either one for use. Different sets thus constructed may operate by power packs, separate batteries, or in any other desired manner.

15 With the above and other objects in view as will be hereinafter apparent, the invention consists in general of certain novel details of construction and combinations of parts hereinafter fully described, illustrated in the accompanying 20 drawings and specifically claimed.

In the accompanying drawings like characters of reference indicate like parts in the several views, and:

Figure 1 is a wiring diagram of the invention. 25 Figure 2 is a plan diagram of the invention.

Figure 3 is an outline front view of one typical arrangement of the apparatus.

Figure 4 is a view similar to Figure 3 but showing a second typical form of the invention. 30

Figure 5 is a view showing one means for coupling the two units.

Figure 6 is a face view of one of the connector terminals.

Figure 7 is a face view of the cooperating 35 terminals.

The invention consists essentially of two receiving sets M and N, a double throw multiple pole switch O and certain conductive connections between various parts. In connection with this 40 apparatus an aerial P and loud speakers R and S belonging respectively to the sets M and N are utilized.

The parts in the two sets necessary to be described for an understanding of the invention will 45 be indicated by like reference characters except that where it is necessary to distinguish a part as belonging to a particular unit it will have the reference character M or N affixed thereto according to which set it belongs.

50 As here shown each set is provided with a radio frequency stage, a detector and two stages of audio frequency amplification. However, this particular arrangement of parts may be varied at will and the arrangement shown in each set is 55 to be understood as being merely a type showing of a standard arrangement or "hook-up". Moreover, each set is shown as provided with the usual binding posts 10 which are indicated as marked in the usual manner common in such sets. These 60 sets will now be described in sufficient detail to enable the invention to be understood. The antenna binding post A is connected by a wire 11 with the antenna transformer primary 12, the secondary 13 of this transformer being connected 65 in the usual manner to the grid and filament of the radio frequency stage tube 14, a variable condenser 15 being bridged across this connection for tuning. At 16 is the radio frequency transformer connected to the grid and filament of the 70 detector tube 17, the plate of this tube being connected to the primary of the first stage audio frequency transformer 18 the secondary of which is in turn connected to the grid and filament of tube 19. The tube 19 has its plate connected to 75 the primary of the second stage audio frequency

transformer 20 the secondary of which is connected to the grid and filament of the tube 21, the plate of this tube being connected to the primary winding of the output transformer 22. The secondary winding of transformer 22 is connected to the loud speaker binding posts (L. S.). A variable condenser 23 is bridged across the grid and filament connections to the tube 17. So far the parts and connections are of standard type but there is now a departure from the usual winding.

80 A switch O here shown as a six pole double throw switch has movable contacts 24, 25, 26, 27, 28 and 29 on one side of which are fixed contacts 30, 31, 32, 33, 34 and 35 and on the other side of which are fixed contacts 36, 37, 38, 39, 40 and 41. The contact 39 is a dead or idle contact.

85 From the plate of tube M14 a wire 42 leads to contact 28 and from the primary of transformer M16 a wire 43 leads to contact 29. Contacts 34 and 35 are connected by a conductor or wire 44.

90 By this means movement of the switch to the left in Figure 1 connects the plate of tube 14 of set M through wire 42, contact 28, contact 34, wire 44, contact 35, contact 29 and wire 43 to the primary of transformer M16. The plate of tube N14 is connected to the primary of transformer N16 by the usual wire 45. The antenna wire 46 extends from the antenna to contact 27

95 and a branch wire 47 connects wire 46 with the antenna binding post A of set M. The contact 33 is connected by a wire 48 with the antenna binding post A of set N. Thus when the switch is turned to the left the antenna binding posts are connected in multiple to the antenna wire 100

105 and the two sets may be tuned to different wave frequencies. From the binding posts (L. S.) of set M run the wires 49 and 50 which are connected respectively to the contacts 24 and 25;

110 and the loud speaker R is connected by wires 115 51 and 52 to the contacts 30 and 31 respectively so that turning the switch to the left connects

loud speaker R to the output transformer M22.

The binding posts (L. S.) of set N are connected by wires 53 and 54 and a switch 70 when 110

120 in its lower position to wires 55 and 56 leading from contacts 36 and 37 to the loud speaker S so that turning the switch O to the right connects the transformers 22 in multiple to the loud speaker S so that this loud speaker, under these 125

conditions receives the combined output of both units. The battery side of the primary of transformer M16 is connected by a wire 57 with contact 38 and contact 26 is connected by a wire 58 with the ground side of the primary N12 of the 130

input transformer of set N. Also the contact 40 is connected by a wire 59 with the wire 48 and contact 41 is connected by a wire 60 with the wire 45.

135 Thus, when the switch is thrown to the right in Figure 1 the antenna circuit is established from antenna P through wire 46, and wire 47 to pass through the primary M12. This affects the operation of the tube M14 which now

140 acts as a first stage tube for radio frequency amplification. From the plate of this tube a circuit is established through wire 42, contact 28, contact 40, wire 48, post A of set N, and through transformer primary N12 which thus affects the 145

operation of tube N14 which acts as a second stage tube for radio frequency amplification. Moreover, the primaries of transformers 16 are connected in multiple through contact 29 and wires 43 and 60.

150 Thus in position to the left the switch O connects the parts for separate operation of the units

while the position of the switch to the right connects the radio frequency stages in series and also connects the audio frequency stages in multiple to a single loud speaker.

5. These special connections may be led to socket plates 61 (Figs. 5 and 6) suitably fixed in any desired position on the cases of the sets and multi-point plugs 62 (Figs. 5 and 7) may carry cables 63 by which the connections may be carried to the switch O.

The two instruments may be arranged in two cases 64 and 65 with a single control dial 66 for each as in Figure 3 or with multi-point dial 67 as in Figure 4. A battery case 68 may carry the switch which may be actuated by a knob 69. The receiving sets and switch may be assembled in a unit to form an integral structure, as shown in Figs. 3 and 4. In fact, there are many arrangements which may be used for housing the units and switch and I do not wish to confine the invention to any particular arrangement since my invention is broader than any specific arrangement for casing and any specific arrangement for connecting the essential instrumentalities employed.

20 The auxiliary switch 70 is provided to supply the output to the reproducer at a high potential or at a low potential. The high potential or up position of the switch will connect the secondaries of the audio transformers of the receivers in series to the reproducer and the low potential or down position of the switch will connect the two secondaries of the audio transformers of the receivers in parallel to the reproducer.

25 There has thus been provided a simple and efficient device of the kind described and for the purpose specified.

30 It is obvious that minor changes may be made in the form and construction of the invention without departing from the material spirit thereof. It is not, therefore, desired to confine the invention to the exact form herein shown and described, but it is desired to include all such as properly come within the scope claimed.

45 Having thus described the invention, what is claimed as new, is:

1. In wireless receiving apparatus, a pair of similar receiving units each having at least one stage of radio frequency amplification, a detector and at least one stage of audio frequency amplification; in combination with a pair of loud speakers, a switch, and connections between said switch and units arranged in one position of the switch to connect the units to respective loud speakers and to connect the radio frequency stage of each unit to the detector of the same unit whereby the sets may be independently operated and arranged in a second position of the switch to connect both units to the same loud speaker and the radio frequency stages of both units in series to the detectors.

2. In wireless receiving apparatus, a pair of similar receiving units each having at least one stage of radio frequency amplification, a detector and at least one stage of audio frequency amplification; in combination with a switch and connections between the switch and units arranged in one position of the switch to permit independent operation of the units and in a second position of the switch to connect the units with their radio frequency stages in series and their audio frequency stages in multiple to a single loud speaker.

3. In wireless receiving apparatus, a pair of similar receiving units each having at least one

stage of radio frequency amplification, a detector and at least one stage of audio frequency amplification; in combination with a pair of loud speakers, a switch, connections between said switch and units arranged in one position of the switch to connect the units to respective loud speakers and to connect the radio frequency stage of each unit to the detector of the same unit whereby the sets may be independently operated and arranged in a second position of the switch to connect both units to the same loud speaker and the radio frequency stages of both units in series to the detectors, an antenna, and connections between said antenna, units and switch arranged in the first position of the switch to connect the radio frequency stages of the units in multiple to the antenna and in the second position of the switch to connect the antenna in series to the series connected radio frequency stages.

4. In wireless receiving apparatus, a pair of similar receiving units each having at least one stage of radio frequency amplification, a detector and at least one stage of audio frequency amplification; in combination with a switch and connections thereto arranged to permit individual operation of the units in one position and cooperative operation in a second position, an antenna, and connections between said antenna, units and switch arranged in the first position of the switch to connect the radio frequency stages of the units in multiple to the antenna and in the second position of the switch to connect the antenna to the series connected radio frequency stages.

5. In wireless receiving apparatus, a pair of similar receiving units each having at least one stage of radio frequency amplification, a detector and at least one stage of audio frequency amplification; in combination with a switch and connections between the switch and units arranged in one position of the switch to permit independent operation of the units and in a second position of the switch to connect the units with their radio frequency stages in series and their audio frequency stages in multiple to a single loud speaker, an antenna, and connections between said antenna, units and switch arranged in the first position of the switch to connect the radio frequency stages of the units in multiple to the antenna and in the second position of the switch to connect the antenna to the series connected radio frequency stages.

6. In wireless receiving apparatus, a pair of receiving units each having at least one stage of radio frequency amplification, a detector and at least one stage of audio frequency amplification; in combination with a pair of loud speakers, a switch, connections between said switch and units arranged in one position of the switch to connect the units to respective loud speakers and to connect the radio frequency stage of each unit to the detector of the same unit whereby the sets may be independently operated and arranged in a second position of the switch to connect both units to the same loud speaker by connecting the radio frequency stages of both units in series to one of the detectors.

7. In a radio broadcast receiver, the combination of a pair of separate radio frequency amplifiers, a detector coupled to each of the radio frequency amplifiers, and a separate translating device coupled to each of the detectors, and means whereby the radio frequency amplifiers may be combined to increase the signal strength in one of the translating devices.

8. A radio broadcasting receiving cabinet embracing a plural number of units, each unit having a detector and an audio frequency amplifier connected thereto to give an independent loud output to a translator, and means to connect the output of the audio amplifiers in multiple or in series to a translator. 80
9. In a radio broadcast receiver, the combination of a pair of separate detector devices, an audio frequency amplifier coupled to each of said detectors, a translating device connected to one of said amplifiers and a second translating device connected to the other of said amplifiers, and means whereby the audio frequency amplifiers of said receiver may be combined to increase the signal strength in one of the translating devices. 85
10. A radio receiving cabinet embracing a plural number of units, each unit having a detector and an audio frequency amplifier connected thereto to give an independent output to a translator and means to connect the output of the amplifiers in multiple series with a translator. 90
11. In a combined plural radio receiver having a plural number of detecting circuits, an individual audio amplifying circuit for each detecting circuit, and means comprising a switch for connecting the outputs of said audio amplifying circuits in series so as to give a high potential output to a translator or in parallel to obtain a high current output at a lower potential. 100
12. In a plural program radio receiving system, a collecting device, a pair of radio receiving sets each comprising a radio-frequency amplifier and a detector, input and output terminals for each of said sets, an individual radio-frequency output connection for one of said radio-frequency amplifiers, a common multiple-point double-throw switch, and connections from the input and output terminals of each of said sets and from said radio-frequency output connection to the points of said switch, said switch being so wired that in one position of said switch the radio-frequency amplifier of one set is connected in series through said radio-frequency output connection to the radio-frequency input of the other set and to said collecting device and the output terminals of said sets are connected in parallel, and in the other position of said switch the input terminals of said sets are connected in parallel to said collecting device. 110
13. In a plural program radio receiving system, a collecting device, a pair of radio receiving sets each comprising a radio-frequency amplifier and a detector, input and output terminals for each of said sets, an individual radio-frequency output connection for one of said radio-frequency amplifiers, a common multiple-point double-throw switch, a plurality of sets of multiple-contact separable plug and sockets members respectively for each of said receiving sets, one member of each of said sets of plug and socket members being mounted on each of said receiving sets and having its contacts connected to said terminals of said receiving set, and the other member of each of said sets of plug and socket members being connected to points of said switch, said switch being so wired that in one position thereof, the radio-frequency input terminals of said sets are connected in parallel to said collecting device and in another position thereof the radio-frequency amplifiers of said sets are connected in series through said radio-frequency output connection to said collecting device. 120
14. In a binary radio receiving system, a collecting device, a first radio receiving set, a companion radio receiving set, each of said sets comprising a radio-frequency amplifier and a detector, input and output terminals for each of said sets, individual separable multiple-contact plug-in connector means mounted respectively on said sets and having contacts connected to the circuits of said sets respectively, and a common multiple-point double-throw switch unit having its points respectively connected to said plug-in connector means and being so wired that in one position of said switch unit the radio-frequency input terminals of said sets are connected in parallel to said collecting device and the output terminals of said sets are separate, and in another position of said switch unit said radio-frequency amplifiers are connected in series to said collecting device and the output terminals of said sets are connected in parallel, whereby said first set and said companion set can be operated together in desired manner by plugging in said connector means in said sets without changing the internal wiring thereof or removing any tubes therefrom. 130
15. In a plural program radio receiving system, a collecting device, a pair of radio receiving sets each comprising a radio-frequency amplifier and a detector, input and output terminals for each of said sets, an individual radio-frequency output connection for one of said radio-frequency amplifiers, and adjustable means for alternatively connecting the radio-frequency input terminals of said sets in parallel to said collecting device or connecting the radio-frequency amplifiers of said sets in series to said collecting device through said radio-frequency output connection. 140
16. In a plural program radio receiving system, a collecting device, a pair of radio receiving sets each comprising a radio-frequency amplifier and a detector, input and output terminals for each of said sets, an individual radio-frequency output connection for one of said radio-frequency amplifiers, adjustable means for alternatively connecting the radio-frequency input terminals of said sets in parallel to said collecting device or connecting the radio-frequency amplifiers of said sets in series to said collecting device through said radio-frequency output connection, and individual two-piece separable multiple-contact plug-in connectors for each of said sets connected from said means to said terminals and said radio-frequency output connection, one piece of each of said connectors being mounted on each of said sets respectively. 150
17. In a plural program radio receiving system, a collecting device, a pair of radio receiving sets each comprising a radio-frequency amplifier and a detector unit, input and output terminals for each of said sets, a common multiple-point double-throw switch, and connections to the points of said switch from the input and output terminals of each of said sets and from the output of each radio-frequency amplifier and from the input of each detector unit, said switch being so wired that in one position of said switch the input terminals of said sets are connected in parallel to said collecting device and said sets operate independently, and in the other position of said switch the detector units of said sets have both their inputs and outputs connected respectively in parallel and the radio-frequency amplifiers of said sets are connected in series between said collecting device and the inputs of said detector units. 160

18. In a plural program radio receiving system, a collecting device, a pair of radio receiving sets each comprising a radio-frequency amplifier, a detector, and an audio-frequency amplifier, 5 input and output terminals for each of said sets, a common multiple-point double-throw switch, individual two-piece separable plug-in connectors for each of said sets, one piece of each of said connectors being mounted on each of said sets respectively and having its contact blades connected to the terminals of said sets respectively, and connections to the points of said switch from the input and output terminals of each of said sets and from the output of each radio-frequency 10 amplifier and from the input of each detector, said switch being so wired that in one position of said switch the input terminals of said sets are connected in parallel to said collecting device and said sets operate independently, and in the other position of said switch the inputs of said detectors and the outputs of said audio-frequency amplifiers are respectively connected in parallel and the radio-frequency amplifiers of said sets are connected in series between said 15 collecting device and the inputs of said detectors. 19. In a plural program radio receiving system, a collecting device, a pair of radio receiving sets each comprising a radio-frequency amplifier and a detector unit, input and output terminals for each of said sets, a common multiple-point double-throw switch, individual two-piece separable plug-in connectors for each of said sets, one piece of each of said connectors being mounted on each of said sets respectively and having its contact blades connected to the terminals of said sets respectively, and connections to the points of said switch through said connectors respectively from the input and output terminals of each of said sets and from the output of each radio-frequency amplifier and from the input of each detector unit, said switch being so wired that in one position of said switch the input terminals of said sets are connected in parallel to said collecting device and said sets operate independently, and in the other position of said switch the inputs and outputs of said detector units are respectively connected in parallel and the radio-frequency amplifiers of said sets are 20 disconnected in series between said collecting device and the inputs of said detector units. 25
